WALTER SCHULZ AND HELLMUT HOFFMANN, OF SYDOWSAUE, NEAR STETTIN, GERMANY, ASSIGNORS, BY MESNE ASSIGNMENTS, TO AMERICAN GLANZSTOFF CORPORATION, OF NEW YORK, N. Y., A CORPORATION OF DELAWARE

METHOD OF HANDLING SPUN CAKES FOR TRANSPORT

Application filed August 30, 1929, Serial No. 389,603, and in Germany January 13, 1929.

The primary object of the present invention is to provide an improved method of handling the so-called cakes of spun artificial silk which are used in factories, located at 5 other places.

The transport of such cakes, whether in a freshly spun condition or after cleansing, otherwise subsequently treating and, it may be drying entails no special difficulties so 10 long as only short distances are involved such as occur in the works. In many cases the well known stiffening rings are left sticking in the cakes for the purposes of transport. When, however, they are sent away from the 15 factory and have to travel long distances, these stiffening rings or corresponding inserted sleeve do not afford the necessary degree of safety and convenience. In the first place, these inner spool-like stiffening rings 20 do not sufficiently protect the spun cake externally and at the ends from injury and shifting of the threads. On the other hand, cakes in this form are far too bulky for transport, as the hollow spaces within the 25 said cakes are wholly unutilized while the external circular form does not permit of rational utilization of packing space.

It has now been found that the packing and transport, even over great distances, of 30 the spun cakes (washed as far as is necessary, decopperized or desulphurized, according to the mode of manufacture, bleached, subsequently treated dyed if necessary washed again, but in any case dried or dry) 35 can be effected in a much more advantageous manner if the cakes be given a definite form departing from the usual ring.

The preferred methods of shaping and packing the cakes are illustrated in the accompanying drawings wherein—

Figure 1 is a perspective view of the usual shape in which the cakes are formed;

Fig. 2 shows a perspective view of a cake when flattened out.

Fig. 3 shows in transverse section a method of stretching a round cake into a flat hank.

Figs. 4, 4a and 4b show, respectively, a front elevation, a top plan and a transverse section, of a type of device for stretching a 50 round cake into flat hank form.

Fig. 4c shows a convenient manner of lacing the cakes.

Figs. 5, 6, 7, 8 and 9 show various ways in which the flattened hanks may be packed for transporting.

A kind of flat hank shape has been found to be best, such as is produced when the round cake *k* shown in Figure 1 is flattened out by directly squeezing it together to the form shown in Fig. 2.

The deformation may be effected either by squeezing the cake together at the sides or by stretching it out radially into a flat hank by means of two inserted ends. The pulling out or stretching of the cakes into 60 a flat hank may conveniently be effected mechanically by putting the cake *k* shown in Figure 3 over two bolts which are then moved apart parallel to each other by means of screw gearing or lever mechanism, thus 65 drawing out the cake to the desired stretched, hanklike shape *s* shown in Figure 4.

It has been found convenient to bind the cakes round, either before or after they are stretched out into hank form with a system 70 of lacing threads, as shown in Fig. 4c.

The retention of the desired form of the cake may, it has been found, also be assured in an original manner by treating the cake with a sleeking composition which causes 80 the threads to adhere to each other. For this purpose the sleeking compositions ordinarily used for artificial silk are suitable; also appropriate wax composition such, for instance, as a composition consisting of bees-

wax 3 parts, Japan wax 3, 5 parts, stearic acid 3, 5 parts and oleic acids or red oil 1 part, melted together and intimately mixed with 20 or more parts of water, in which 1 part of caustic soda is dissolved, or sleeking 85 compositions which contain soaps or even consist solely thereof. The sleeking solution or emulsion is not made too strong but

only just strong enough to secure a useful degree of mutual adhesion between the 90 threads. Such adhesion takes place even if only comparatively thin sleeking solutions be used, which do not stick the cakes up to

such an extent as to interfere with the subsequent unwinding thereof. The sleeking of 100

the cakes when carried out within modest limits has even been found advantageous in unwinding, as the single threads are thereby rendered less liable to drop.

5 The cakes may now be packed singly and in doing so care must be taken that when packed and transported they do not lose the aforesaid desired compressed, hank-like form *s*. For this purpose they are laid as 10 shown in Figure 5 between two stiffening plates *a* and *b* which are corded up together with the cakes or held together in any manner under pressure. Between these stiffening plates neither the cake hank as a whole, 15 nor the single layers of thread, nor the individual threads can shift. Instead of two separate stiffening plates a single stiffening plate can also be used which is folded together in the shape of a U as shown in Figure 20 6.

As shown in Figures 7 and 8 there may also be placed simultaneously between the same stiffening plates *a* and *b* a number of 25 cake hanks arranged one beside another and lying in one plane; for instance, four six or nine such hanks may be so arranged.

As a stiffening material thick paper, cardboard, papier-mâché, wood, artificial substances or, it may be, light metal and the 30 like may be used.

The various small parcels thus formed may then conveniently be packed together into larger bundles or placed in pasteboard boxes and these then packed in the usual cases.

35 Instead of packing each cake separately it has been found very convenient to pile them column-wise one on top of another (as shown in Figure 9, for example) in a pasteboard box *p* or the like. In such case it is 40 convenient to lay a sheet of paper *q* or a sheet of cardboard or the like in between the several cakes *s*. When the cakes are placed in a pasteboard box or other solid envelope of that kind, it is advantageous to line the interior thereof with tissue paper *o* or oiled paper or the like.

At the foot of the pile and at the top thereof of a thicker sheet of cardboard or even a thin wooden sheet *h* or the like may be used 50 which may extend either over one pile or simultaneously over several piles. In either case these sheets prevent the deformation of the piles when tying them up and they may, in some cases, simultaneously hold a number 55 of piles together. The pile or piles so formed, and it may be, placed in the pasteboard box are subjected to pressure from above and, if necessary, tied up under this pressure with the pasteboard box. In this parcel neither the 60 several spun cakes pressed together nor individual threads can shift thus, when the parcel is opened after transport they are found to have remained still in the same position as when packed.

65 It has been found and is worthy of particu-

lar notice that the spun cakes so formed into flat hanks, and thus packed and transported, can very easily be further treated after the parcel has been opened. This may take place in various ways. Thus the flat 70 hanks may be again opened out into a ring the well known rubber or celluloid, springy, elastic stiffening rings or the like may be again inserted, after which the thread may be drawn off endwise in the well known manner, whether it be for transference to reels in the hank form or for winding onto cross wound bobbins, bottle shaped bobbins, cops or the like.

Again, a reel-like supporting device may, 80 be inserted in the flat cake hanks and the cake hank wound off tangentially by rotating it, like an ordinary hank. This novel mode of winding off spun cakes has been 85 found to be specially advantageous for the purpose of dealing with spun cakes handled by the methods of the present invention.

What we claim is:—

1. A method for treating purified and dried 90 spun cakes of artificial silk, which are used in distant factories consisting in subjecting the annular cake to stretching along one diameter thereof until the cake assumes the form of a substantially flat hank and transferring the hank so formed to a place where thread is withdrawn from the cake.

2. The method according to claim 1, wherein in two rods inserted in the central opening of the annular cake are moved apart, while 100 maintaining them parallel until the cake has been stretched and has assumed a hank-like shape.

3. A method of treating purified and dried 105 spun cakes of artificial silk, which are used in distant factories consisting in securing the mutual position of the threads therein, causing the annular cake to be expanded in one diametral direction until the cake assumes the form of a substantially flat hank and transferring the hank so formed to a place where thread is withdrawn from the cake.

4. A method of treating purified and dried 115 spun cakes of artificial silk, which are used in distant factories consisting in lacing the cake around with threads, causing the annular cake to be expanded in one diametral direction until the cake assumes the form of a substantially flat hank and transferring the hank so formed to a place where thread is withdrawn from the cake.

5. A method of treating purified and dried 125 spun cakes of artificial silk, which are used in distant factories consisting in causing the annular cake to be expanded in one diametral direction until the cake assumes the form of a substantially flat hank, lacing such hank with threads and transferring the hank to a place where thread is withdrawn from the cake.

6. A method of handling a spun cake of artificial silk said method consisting in treating the purified cake to secure partial adhesion of the threads therein, drying the cake, causing the annular cake to be expanded in one diametral direction until the cake assumes the form of a substantially flat hank and transferring the hank so formed to a place where thread is withdrawn from the cake. 70
7. A method of handling a spun cake of artificial silk said method consisting in treating the purified cake with a sleeking composition to produce mutual adhesion between the threads, drying the cake causing the annular cake to be expanded in one diametral direction until the cake assumes the form of a substantial flat hank and transferring the hank so formed to a place where thread is withdrawn from the cake. 80
8. A method of handling a spun cake of artificial silk said method consisting in causing the dried annular cake to be expanded in one diametral direction until the cake assumes the form of a substantially flat hank, compressing the hank, packing the same, transferring the hank in compressed packed condition to a place where thread is to be withdrawn from the cake and unpacking and relieving the pressure before subjecting the thread in the hank to further operations. 90
9. A method of handling a spun cake of artificial silk said method consisting in treating the cake to secure the mutual position of the threads therein, causing the dried annular cake to be expanded in one diametral direction until the cake assumes the form of a substantially flat hank, compressing and packing said hank, transferring the hank in compressed packed condition to a place where thread is to be withdrawn from the cake and unpacking and relieving the pressure before subjecting the thread in the hank to further operations. 100
10. The method according to claim 8 wherein a plurality of prepared hanks are arranged side by side between common packing members through which pressure is applied simultaneously to all of such hanks before the same are packed. 110
11. A method of handling spun cakes of artificial silk, said method consisting in treating the cake to secure the mutual position of the threads therein, causing the dried annular cake to be expanded in one diametral direction until the cake assumes the form of a substantially flat hank, compressing each hank so formed between stiffening members, packing a plurality of such compressed hanks together columnwise in a container, transporting said container to a place where the thread is to be further handled, unpacking and decompressing the hanks and subsequently transferring the thread from each hank to thread carrying means. 120
12. A method of handling spun cakes of artificial silk, said method consisting in treating the cake to secure the mutual position of the threads therein, causing the dried annular cake to be expanded in one diametral direction until the cake assumes the form of a substantially flat hank, compressing each hank so formed between stiffening members, packing a plurality of such compressed hanks together columnwise in a container, transporting said container to a place where the thread is to be further handled, unpacking and decompressing the hanks, mounting each hank on a hank carrying device and subsequently transferring the thread from each hank to thread carrying means. 125
13. A method of handling spun cakes of artificial silk, said method consisting in treating the cake to secure the mutual position of the threads therein, causing the dried annular cake to be expanded in one diametral direction until the cake assumes the form of a substantially flat hank, compressing each hank, packing a plurality of such compressed hanks together columnwise with interposed protecting sheets in a protectively lined container, transporting said container to a place where the thread is to be further handled, unpacking and decompressing the hanks and subsequently, transferring the thread from each hank to thread carrying means. 130
14. A method of handling spun cakes of artificial silk, said method consisting in treating the cake to secure the mutual position of the threads therein, causing the dried annular cake to be expanded in one diametral direction until the cake assumes the form of a substantially flat hank, compressing each hank, packing a plurality of such compressed hanks together columnwise with interposed protecting sheets and with stout top and bottom stiffening sheets in a protectively lined container, transporting said container to a place where the thread is to be further handled, unpacking and decompressing the hanks and subsequently, transferring the thread from each hank to thread carrying means. 140
15. A method of handling spun cakes of artificial silk, said method consisting in treating the cake to secure the mutual position of the threads therein, causing the dried annular cake to be expanded in one diametral direction until the cake assumes the form of a substantially flat hank, compressing each hank, packing a plurality of such compressed hanks together columnwise with interposed protecting sheets and with stout top and bottom stiffening sheets compressing the column while parcelling it into a single bundle, transporting the bundle to a place where the thread is to be further handled, unpacking and decompressing the hanks and subsequently, transferring the thread from each hank to thread carrying means. 150

16. A method of handling spun cakes of artificial silk, said method consisting in treating the cake to secure the mutual position of the threads therein, causing the dried annular cake to be expanded in one diametral direction until the cake assumes the form of a substantially flat hank, compressing each hank, compressing a plurality of such hanks into a pile with interposed protective sheets, 10 stout top and bottom stiffening plates and a covering protecting the edges of the hanks, transporting the bundle so formed to a place where the thread is to be further handled, unpacking the hanks and expanding them substantially to the original annular cake 15 shape and finally withdrawing thread from each cake on to another carrier device.

17. A method of handling spun cakes of artificial silk, said method consisting in 20 treating the cake to secure the mutual position of the threads therein, causing the dried annular cake to be expanded in one diametral direction until the cake assumes the form of a substantially flat hank, compressing each 25 hank, compressing a plurality of such hanks into a pile with interposed protective sheets, stout top and bottom stiffening plates and a covering protecting the edges of the hanks, transporting the bundle so formed to a place 30 where the thread is to be further handled, unpacking the hanks and expanding them substantially to the original annular cake shape, mounting each annular cake so formed on a stiffening carrier and finally withdrawing 35 thread from each cake on to another carrier device.

18. A method of handling spun cakes of artificial silk, said method consisting in treating the cake to secure the mutual position of the threads therein, causing the dried annular cake to be expanded in one diametral direction until the cake assumes the form of a substantially flat hank, compressing each hank, compressing a plurality of such hanks 45 into a pile with interposed protective sheets, stout top and bottom stiffening plates and a covering protecting the edges of the hanks, transporting the bundle so formed to a place where the thread is to be further handled, 50 unpacking the hanks and expanding them substantially to the original annular cake shape, mounting each annular cake so formed on a stiffening cylindrical carrier and finally withdrawing thread endwise 55 from each cake on to another carrier device.

19. A method of handling spun cakes of artificial silk, said method consisting in treating the cake to secure the mutual position of the threads therein, causing the dried 60 annular cake to be expanded in one diametral direction until the cake assumes the form of a substantially flat hank, compressing each hank, compressing a plurality of such hanks into a pile with interposed protective sheets, 65 stout top and bottom stiffening plates and a

covering protecting the edges of the hanks, transporting the bundle so formed to a place where the thread is to be further handled, unpacking the hanks and expanding them substantially to the original annular cake 70 shape, mounting each annular cake so formed on a reel-like supporting device and withdrawing thread tangentially by rotating.

20. A method of handling spun cakes of artificial silk said method consisting in treating the cake to secure the mutual position of the threads therein, causing the dried annular cake to be expanded in one diametral direction until the cake assumes the form of a substantially flat hank, compressing each 80 hank, compressing a plurality of such hanks into a protectively lined container with interposed protective sheets and stout top and bottom stiffening plates, transporting the bundle so formed to a place where the thread 85 is to be further handled, unpacking the hanks and mounting each hank on a reel-like supporting device and withdrawing thread tangentially by rotating.

In witness whereof, we have hereunto signed our names.

WALTER SCHULZ.
HELLMUT HOFFMANN.
